PROTECTIVE SIGNAL SYSTEM

Clarence C. C. Eggers, Minneapolis, Minn., assignor of one-half to Calvin E. Holmes, Minneapolis, Minn.

Application December 15, 1934, Serial No. 757,629

7 Claims. (Cl. 177—369)

My invention relates to protective signal systems and particularly to remotely operated systems for indication at a central station and has for an object to provide a system which may be used for the indication of burglaries, rise or fall in temperature, increase or reduction in pressure or for any of the other uses for which protective systems may be employed.

An object of the invention resides in providing a system which is positive in action and which cannot be tampered with in any manner without causing actuation of the system and indication of the fault.

A still further object of the invention resides in providing a system in which the particular locality at which the variation in condition or disturbance occurs can be indicated at the central station.

An object of the invention resides in providing a system including a circuit which is adapted to operate a signal if the circuit is grounded, or opened, or any portion thereof shunted out or shorted, or if any combination of shunting, shorting, grounding or opening any portion of the circuit is attempted.

An object of the invention resides in utilizing a circuit including a main line running from the central station to a subscriber's station, said main line being connected at one end to a source of electrical energy disposed at the central station and being grounded at its other end in the central station.

A still further object of the invention resides in providing at the central station in said line and at the grounded side thereof a relay and in providing at the subscriber's station a protective device adapted to open said circuit in the event that the normal condition of the circuit at the subscriber's station is disturbed.

Another object of the invention resides in providing at said central station a potential relay in said circuit and in further providing a resistance in series with said protective device and disposed in close proximity thereto.

An object of the invention resides in providing at said central station a signal circuit adapted to be energized by either or both of said relays, said signal circuit having one or more signals therein for indicating a defect in said circuit, tampering with or intentional operation of the system through said first named circuit.

Another object of the invention resides in providing a call device in said first named circuit and in providing a recording device in said signal circuit adapted to be operated by said call device.

A still further object of the invention resides in providing a secondary circuit at the subscriber's station similar to said signal circuit at the central station for operating said call device.

A feature of the invention resides in providing a subscriber's operating circuit for closing said secondary circuit.

An object of the invention resides in disposing in said subscriber's operating circuit a protective device for operating said circuit.

Another object of the invention resides in connecting said subscriber's operating circuit at one end to a source of electrical energy and at its other end to the ground.

A feature of the invention resides in providing a relay having a coil connected in said subscriber's operating circuit at the grounded side thereof and having switch elements disposed in said secondary circuit.

Another object of the invention resides in providing a second potential relay having a coil connected in said subscriber's operating circuit and having switch elements connected in said secondary circuit and in further providing a resistance in series with said protective device and in close proximity thereto.

A still further object of the invention resides in utilizing a manually wound spring actuated call device and in providing an electrically operated trip device therefor, said trip device including an electromagnet connected in said subscriber's operating circuit.

An object of the invention resides in the specific construction of said call device.

A feature of the invention resides in providing manually operated switches for closing and grounding said operating circuits.

An object of the invention resides in the specific construction of said switch and in the circuits associated therewith.

Other objects of the invention reside in the novel combination and arrangement of parts and in the details of construction hereinafter illustrated and/or described.

In the drawings:

Fig. 6 is an elevational view of the cam key used with the invention.

Fig. 7 is a wiring diagram of the portion of the system associated with the cam key shown in Fig. 6.

Fig. 8 is an across-the-line wiring diagram of the system shown in Fig. 1.

In designing protective systems it has heretofore been customary to provide a protective system for a single designated purpose as for example to indicate fire or burglary or failure of sprinkler systems or some other single purpose. The present invention provides a system which may be used for any and all such purposes and for any other purpose which the subscriber may desire without additional main lines. With the protective systems now in use a protective device may be rendered inoperative by competent mechanics so that the purpose of the system is obstructed and the system frequently fails to operate at the critical time. The present invention provides a device which may be used for any desired purpose and may be used for several desired purposes at one time and which cannot be tampered with without causing operation of the signal.

My invention as shown in Fig. 1, includes a signal circuit indicated in its entirety by the reference numeral 10 and an operating circuit 30 therefor indicated in its entirety by the reference numeral 11. The circuit 11 includes a main line 12 having sides 13 and 14 which run between a central station C and a subscriber's station S. At the subscriber's station S there are various substations a, b, c, d, e, f and g, at which stations suitable protective devices are installed, for indicating at the central station the existence of certain conditions at the subscriber's station. At certain of the above named stations namely stations e, f and g, are located call devices 15, 16 and 17 which are adapted to operate a recording device 18 in the signal circuit 10 and to designate in addition to giving the desired signal the particular station from which said signal originates. For the purpose of operating these call devices and to prevent tampering therewith or with the circuits connected with the same, a secondary circuit 19 is employed which is similar to the signal circuit 10. This circuit is operated 50 by a subscriber's operating circuit 21 which is similar to the operating circuit previously referred to. These various circuits and the apparatus connected therein will now be described in detail.

55. Electrical energy is provided at the central station for both of the circuits 10 and 11 by means of a generator 22 which is connected on one side through a conductor 23 to the ground. The other side is connected through a conductor 60 24 with two variable resistances 25 and 26 arranged in parallel. The generator 22 delivers a voltage considerably greater than that desired to be used in the circuits 10 and 11 and the resistances 25 and 26 are employed to cut down 65 the voltage to that desired. The signal circuit 10 includes a local line 28 which comprises two conductors 29 and 31. Conductor 29 is directly connected to the resistance 25, being thereby connected to the potential side of the generator 22. Conductor 31 is directly connected to ground. In the signal circuit 10 is provided in addition to the recording device 18 a bell or other resonant signal 33, an annunciator 34 and a light 35. A conductor 32 forms part of the circuit 10 and is 70 directly connected to the recording device 18.

Branch conductors 36 and 37 connect the conductor 32 with the bell 33 and the coil 38 of the annunciator 34. The annunciator 34 is constructed with a swinging armature 39 which operates a trip lever 41. A swinging arm 42 is held in position by means of the trip lever 41. When the armature 39 is articulated by the coil 38, arm 42 is released and drops downwardly to a position shown in dotted lines at 43. This arm forms part of the signalling circuit 10 and is adapted to engage a contact 44 when in its lowermost position. The contact 44 is connected through a conductor 45 with the lamp 35 while the arm 42 is connected through a conductor 46 with the conductor 29. The other side of the lamp 35 is 15 directly connected to the conductor 31.

The circuit 10 is normally open, being broken between the conductors 29 and 32. For the purpose of closing this circuit, three relays 47, 48 and 49 are employed which are constructed in 20 the following manner: The relay 47 is provided with a coil 51 and two contacts 52 and 53 adapted to be connected through a connector 54. Connector 54 is operated by a plunger 55 which is drawn into the coil 51 when the said coil is energized and serves to connect the contacts 52 and 53 together, thereby forming a switch which I have indicated in its entirety by the reference numeral 56. A spring 60 attached to connector 54 holds said switch open. The relay 47 is a 30 potential relay and operates only when the potential across the coil 51 is increased beyond a normal predetermined potential insufficient to cause the closing of the switch 56. Relay 48 is constructed with a coil 57 and plunger 58 movable 35 within the same. Plunger 58 operates a connector 59 which is adapted to connect together two contacts 61 and 62. These contacts and connector constitute another switch which I have indicated in its entirety by the reference numeral 64. Coil 48 normally holds the switch 64 open and when said coil is deenergized the spring 63 draws the connector into engagement with contacts 61 and 62 and closes said switch. The relay 49 is identical with relay 48 and comprises a coil 65 and a plunger 66 movable within 45 the same. This plunger has attached to it a connector 68 which is adapted to connect together two contacts 69 and 71 and forms in conjunction therewith a switch indicated in its entirety by the reference numeral 72. A spring 73 similar to the spring 63 serves to close the switch 72 when the coil 65 is deenergized. Both of the relays 48 and 49 are current relays and are adapted to hold the switches 64 and 72 open as long 50 as current flows through the coils 51 and 65 and are adapted to close said switches when said coils are deenergized.

The contact 52 of relay 47 is connected through a conductor 74 with conductor 29 previously referred to. Another conductor 75 connects contact 53 with conductor 32. Contact 61 of relay 48 is connected through a conductor 76 with conductor 29 and contact 62 is connected through a conductor 77 with conductor 32. Conductors 65 29 and 32 are directly connected to the contacts 69 and 71 of relay 49. It will thus be seen that the three switches 56, 64 and 72 are connected in parallel across the local line 28 forming part of the signal circuit 10 and that the operation of 70 any or all of said relays will close the signal circuit and procure operation of the various signalling devices contained in the same.

As previously stated, current for energizing the operating circuit 11 is procured from the gener- 75

ator 22. For this purpose the resistance 26 is employed which has connected to it a conductor 101. This conductor is in turn connected to a rheostat 102 which is further connected to a conductor 103. Conductor 103 feeds the various relays 47, 48 and 49 and is connected in the circuit 11 as will be presently described in detail.

For the purpose of testing the control circuit 11 two test jacks 78 and 79 are employed. The jack 78 comprises four leaves 81, 82, 83 and 84. The leaves 81 and 82 are adapted to contact with one another and the leaves 83 and 84 are similarly adapted to contact with one another when the jack is in normal position. The two outer leaves 81 and 84 are formed with extensions 85 and 86 which are adapted to be connected to a suitable test plug, not shown, when the same is inserted in the jack. Jack 79 is similarly constructed and consists of outer leaves 87 and 88 and inner leaves 89 and 91 adapted to contact with the outer leaves. The outer leaves are constructed with extensions 92 and 93 which are adapted to be connected to the plug used for the testing of the circuit. It will be noted that the outer leaves of both of the jacks 78 and 79 are normally connected to the inner leaves and that when the outer leaves are spread apart and the plug inserted into the jack, the jack 78 is connected in the side 14 of line 12 while the jack 79 is connected in side 30 13 of said line.

The manner of connecting the jacks in the circuit will now be described. Side 14 of line 12 is connected to leaf spring 81 of jack 78 while a conductor 94 is connected to the other outer leaf 84 and to the other end of the coil 65 of relay 49. The other end of this coil is connected through a conductor 95 with the ground. The two leaves 82 and 83 of the jack 78 are connected together so that when the jack is in normal position continuity of the circuit occurs successively through the leaves 81, 82, 83 and 84. The jack 79 is similarly connected. Side 13 of line 12 is directly connected to the leaf 87 thereof, while the leaf 88 is connected to a conductor 96. This conductor 45 is in turn connected to the end of coil 51 of relay 47. A branch conductor 97 is connected to the conductor 96 and is also connected to the other end of coil 51 of relay 48. The other ends of these relays are connected to a conductor 98 50 which in turn is connected to the conductor 103 previously referred to. It will thus be seen that the coil 65 of relay 49 is connected in the side 14 of line 12 and is directly grounded and that the two coils 51 and 51 of relays 47 and 48 are 55 connected in parallel and are in the other side 13 of the line, being disposed on the potential side of the line.

As previously stated the line 12 extends between the central station C and the subscriber's station S, the said line being of any desired length and taking any suitable course necessary to connect the subscriber's station with the central station. The remainder of the apparatus and the equipment utilized with the invention is situated 60 at the subscriber's station and at the various substations of the subscriber's station. The portion of the circuit 11 at the subscriber's station consists of a number of conductors which are connected to the various protective devices, said devices being all arranged in series in said circuit.

At the various sub-stations *a, b, c, d, e, f* and *g*, a protective device has been installed which is connected in the circuit 11. Inasmuch as the system may be used for various purposes, different 75 types of protective devices have been shown and

it can readily be comprehended that the type of device disclosed is merely illustrative and that any type of device may be substituted for that disclosed.

At station *a* I have shown a pressure responsive switch 403 which is particularly adapted to be used in conjunction with a sprinkler system. This switch includes a case 104 which is provided with a chamber 105 within the interior thereof. Case 104 is open at the front and is adapted to be closed by means of a diaphragm 106 secured thereto through a retaining ring 107 and machine screws 108. Diaphragm 106 carries a contact 109 which is adapted to engage a contact 111, said contacts forming in conjunction a switch indicated in its entirety by the reference numeral 112. The case 104 is connected to a suitable pipe 113 which communicates with the water supply system of the sprinkler system. A spring 114 acting between the diaphragm 106 and case 104 holds the switch 112 normally open. The pipe 113 communicates with chamber 105 and when the pressure within the chamber 105 is normal, switch 112 is closed. If for any reason the water pressure drops below normal, the diaphragm 106 25 will be drawn inwardly through the action of spring 114 and switch 112 will open. This will cause the operation of the signalling system in a manner to be presently described in detail.

At stations *b* and *c* are located thermostats 115 and 116. The thermostat 115 consists of a spiral 117 of bi-metal which is adapted to contact with a fixed contact 118. This construction forms a switch 119 which is normally maintained closed. Thermostat 116 similarly consists of a spiral of 35 bi-metal 121 which is adapted to engage a contact 122. This construction provides a switch 123 which is also normally closed. The thermostats 115 and 116 may be so constructed that the switches thereof open when an increase of 40 temperature occurs. In such case the said thermostats are used for indicating fire or any abnormal rise in temperature such as might be occasioned in commercial plants where constant temperature is essential in the manufacture of its 45 goods or products. The thermostats 115 and 116 may also be constructed so that the switches thereof open upon an abnormal drop in temperature. Such device may be advantageously used for safeguarding against freezing of water in pipes 50 or other systems or for abnormal refrigeration or abnormal drop in temperature in any system.

At stations *c* and *f* window foil 124 and 125 has been illustrated as installed on two windows 126 and 127. This foil serves in the usual manner to give a signal when the window has been opened or broken or the circuit in any other manner tampered with at such locality. The foil 124 and 125 is cemented to the window and forms a direct part of the circuit. The method of use of the foil 124 and 125 is obvious. Said foil may be used in conjunction with any closure or structure which is apt to be broken or tampered with. It can readily be comprehended that a simple window switch may be substituted in place of the foil 65 shown or may also be used in conjunction with the foil, if desired.

Where the protective system is to be used in a bank or similar place of business, it becomes frequently desirable to permit the attendants or employees in the bank to manually operate the system and give the signal. For this purpose cam keys 128 and 129 have been shown at stations *d* and *g*. These cam keys will be presently described in detail.

With my improved invention the particular location of origin of the signal may be accurately indicated at the central station. This is accomplished through the various call devices 15, 16 and 17 which are situated at the desired substations in the subscriber's station. With my invention some of the stations may have such call devices and other stations may be operated without the call device, a general alarm being in such case sounded. For the purpose of illustration, call devices have been shown at stations e, f and g, though it can readily be comprehended that the said devices may be placed at any or all of the other stations shown, if desired. If the call devices were directly connected to the protective devices the same might be tampered with and shorted out so as to prevent the rendering of the signal. To overcome this disadvantage the circuits 19 and 21 have been employed in association with the call devices and the other equipment of the invention, which circuits will be subsequently more fully described.

Inasmuch as both of the cam keys 128 and 129 and the method of connecting up the same are identical, only the key 128 will be described in detail. The construction of the said key is shown in Fig. 6, while the wiring diagram for the portion of the circuit 11 associated therewith is shown in Fig. 7. The key 128 comprises a frame 131, U-shaped in form which is constructed with two legs 132 and 133 and a connecting portion 134. Between the two legs 132 and 133 is mounted a bar 135 which is riveted or otherwise secured to the said two legs. This bar carries the various switch elements of the key. The switch elements of the key are formed through a number of switch leaves which are arranged in groups. There are four groups designated at 136, 137, 138 and 139 and the switch leaves in each group are similarly constructed. The two groups 136 and 137 are disposed on one side of the bar 135 while the groups 138 and 139 are disposed on the other side of said bar directly in back of the first named groups and the leaves thereof are hence not fully visible in Fig. 6. Group 136 includes three leaves 141, 142 and 143 of which the inner leaf 142 is adapted to move between the leaves 141 and 143 and to make contact with either thereof, depending upon the relative positions of said intermediate leaf. The leaves 141 and 143 have contacts 144 and 145 which are adapted to directly engage the leaf 142. To limit the movement of the leaf 142 a rigid leaf 146 is employed which is disposed between the leaves 142 and 143. All of these leaves including the strip 146 are separated from one another through insulating spacers 147 and the entire group is held in place by means of screws 148 which pass through the said leaves and spacers and are insulated from the leaves through sleeves encircling said screws, which structure has not been shown in the drawings. Screws 148 screw into a mounting block 149 which is held attached to the bar 135 on one side thereof by means of a screw 151. The group 137 includes leaf springs 152, 153 and 154 which are constructed identical with the leaves of the group 136 and which are similarly separated through insulated spacers 155. This group of springs is attached by means of screws 156 to the block 149, the same as the group 136 and is disposed on the opposite side of said block. Group 138 includes leaves 157, 158 and 159 and group 139 includes leaves 161, 162 and 163. All of these leaves are mounted in identically the same manner as the leaves of the previous group

and are attached to the bar 135 on the opposite side thereof.

For operating the key, a cam lever 164 is employed which consists of a plate-like portion 165 arcuate in form which is pivoted between two ears 166 formed on the connecting portion 134 of frame 131. A pin 167 passes jointly through said ears and plate-like portion and forms a pintle on which said cam lever swings. A handle 168 is attached to said cam lever and serves as a means for manipulating the same. The plate-like portion 165 has attached to it a pin 169 which has mounted on opposite sides thereof rollers 171. These rollers are constructed of insulating material such as fiber or any of the phenol formaldehyde products. One of the rollers 171 is adapted to engage cams 172 and 173 formed on the switch leaves 142 and 153 and the other of said rollers is adapted to engage similar cams formed on the switch leaves 158 and 162, as best shown in Fig. 7. When the cam lever is swung downwardly as viewed in Fig. 6, roller 171 moves the cam 172 upwardly breaking the circuit between leaves 142 and 143 and connecting a circuit including leaves 141 and 142. When the handle 168 is moved upwardly, roller 171 operates in the same manner with reference to leaf 153 opening the circuit through leaves 152 and 153 and connecting a circuit through leaves 153 and 154. At the same time a corresponding opening and connecting of the leaves of groups 138 and 139 occurs, due to the other roller 171 on the opposite side of the plate-like member 165 of the cam lever 164.

The various leaves of the cam key 128 are connected together as shown in Fig. 7. A conductor 174 connects the leaves 141 and 163 together. A conductor 175 connects the leaves 143 and 159 together. Another conductor 176 connects the leaves 152 and 161 together. A conductor 177 connects the leaves 153 and 162 together and a conductor 178 connects the two leaves 154 and 157 together. The other conductors of the cam key are connected in the circuit 11 as will be subsequently more fully described.

The three call devices 15, 16 and 17 being identical in construction, only the call device 15 will be described in detail which is shown in Figs. 2, 3, 4 and 5. This device comprises a panel 181 constructed of insulating material which is mounted upon a base 182. The plate 181 is smaller in dimensions than the base 182 which projects marginally outwardly beyond the same. Enclosing the entire mechanism is a case 183 constructed with side walls 184 and 185 and with end walls 186 and 187. A top 188 is connected to all of said walls. The lowermost portion of case 183 is open and is of such dimensions as to fit about the panel 181. The lowermost edges of the walls 184, 185, 186 and 187 rest directly upon the base 182. Case 183 is secured to the base 182 by means of countersunk machine screws 189 which are screwed into angle brackets 191 attached to the walls 184 and 185 of the case proper.

The call device includes an electromagnet 192 which is mounted upon the panel 181. This electromagnet consists of two cores 193 and 194 attached to a yoke 195. About the cores 193 and 194 are wound coils 196 and 197. The electromagnet 192 is attached to the plate 181 by means of countersunk machine screws 198 which extend through the panel 181 and are threaded into the core structure of the electromagnet. The electromagnet 192 further includes an upright 199 con-

structed with a base portion 201. This base portion is attached to the panel 181 by means of countersunk machine screws 202 which are threaded into said base portion and which extend through the panel 181. At the upper end of the upright 199 is provided a forked bearing 204 which rotatably supports a pintle 205. Secured to the pintle 205 is an armature 206 formed with a cross head 208 adapted to be attracted by the free ends of the cores 193 and 194 of the magnet 192. A screw 207 is threaded into the armature 206 and engages a member 208 extending outwardly from the upright 199. This screw limits the downward movement of the armature 206 and prevents the cross head 208 from sticking to the ends of the cores 193 and 194. Issuing upwardly from the member 208 is a bracket 209. An adjusting screw 211 is threaded in this bracket and engages the armature 206 and serves as a limit for the upward movement of the same. By means of this screw the cross head 208 is prevented from moving too far away from the magnet. A compression coil spring 212 acting between the armature 206 and the member 208 urges the said armature away from the cores 193 and 194 and causes the said armature to normally assume the position shown in Figs. 3 and 5.

For operating the call device a clock mechanism is employed which is indicated in its entirety by the reference numeral 213. This clock mechanism comprises two bearing plates 214 and 215 which are constructed at their lower ends with flanges 216 and 217. Countersunk machine screws 218 pass through the panel 181 and are threaded into the said flanges. Spacer sleeves 219 are disposed between the bearing plates 214 and 215 and machine screws 221 pass jointly through said plates and sleeves and hold the plates assembled in spaced parallel relation. Journaled in the two plates 214 and 215 is a main arbor 222 which projects beyond the plate 214 and has attached to it one end of a spiral spring 223. The other end of this spring is attached to a post 224 secured to the plate 214. The other end 225 of arbor 222 projects outwardly through an opening 226 in the wall 185 of case 183 and has attached to it a finger plate 227 by means of which the arbor 222 may be rotated. Between the two plates 214 and 215 is rotatably mounted on the arbor 222 a gear wheel 228. This gear wheel has attached to it a pawl 229 (Fig. 5) which is adapted to engage a ratchet 231 rigidly secured to arbor 222. A C spring 232 attached at one end to gear wheel 228 engages at its other end the pawl 229 and holds the same into engagement with the ratchet 231. The gear wheel 228 meshes with a gear pinion 233 fast on another arbor 234. This arbor is similarly journaled in the two bearing plates 214 and 215. Arbor 234 has attached to it a gear wheel 235 which in turn meshes with another gear pinion 236. Pinion 236 is fast on an arbor 237 which similarly is journaled in the two bearing plates 214 and 215. Arbor 237 has secured to it an escape wheel 238 which cooperates with an escapement 239 mounted on an arbor 241. This arbor is also journaled in the bearing plates 214 and 215. When the spring 223 is wound up rotary movement is imparted through the gear train to the escape wheel 238 which imparts an oscillatory movement to arbor 241. Attached to the arbor 241 is a weight 242 which times the oscillation of the arbor 241. This controls the time taken for the spring to unwind

and gives sufficient time for the operation of the call device.

The call device includes a switch mechanism best shown in Figs. 2 and 4. This switch mechanism comprises a mounting block 243 which is constructed of fiber or some other similar insulating material. The mounting block 243 is secured to bearing plate 215 by means of machine screws 244 which extend through the said block and are threaded into said bearing plate. Attached to the mounting block 243 are two switch leaves 245 and 246 constructed of spring material which are formed at their ends with ears 247 bent outwardly therefrom. Rigidly secured to the arbor 234 is a hub 248 which has attached to it two disks 251 and 252. The disk 251 is constructed with a certain number of notches 253 which are spaced in a predetermined manner. The ear 247 of switch spring 246 is adapted to engage the peripheral surface of the disk 251 and operates to close the circuit when in contact therewith. When said ear comes opposite the notches 253 the circuit through said switch leaf is opened. The disk 252 is smaller in diameter than the disk 251 and is constructed at intervals about its periphery with outwardly projecting lugs 254. These lugs are adapted to be engaged by the ear 247 of the leaf spring 245. When the lug 254 is engaged with the leaf spring 245 the circuit through the said leaf spring is grounded. When, however, the ear 247 of said spring is intermediate the lugs 254 the circuit through the said leaf spring is opened. The lugs 254 correspond in number and position with the notches 253 and when the two switch leaves 245 and 246 are in the same plane and the ears 247 thereof at the same location the said lugs register with the notches. As the arbor 234 rotates circuits are successively opened and grounded operating in a manner to cause the recording device 18 to function and thereby make a record in the recording device which indicates the particular station at which the call device originated.

The arbor 222 is held from movement by means of a latching device best shown in Figs. 2 and 3. The armature 206 of the electromagnet 192 has attached to it an upright 255, which is provided at its outer end with a latch lug 256. This lug is adapted to engage a finger 257 formed on an arm 258. Arm 258 is secured to the arbor 222. When the parts are in normal position the finger 257 rests upon the latch lug 256 as shown in Fig. 3. When the armature 206 of the electromagnet is attracted by the core of the same, the arm 255 is swung toward the left as viewed in Fig. 3 and the latch lug 256 is disengaged from the finger 257. Arbor 222 then commences to rotate, at the same time rotating arbor 234 and the two disks 251 and 252 attached thereto in the direction indicated by the arrow in Fig. 2. This successively makes and breaks the respective circuits controlled by said disks.

After the arbor 234 has made a complete revolution a pin 259 fast on disk 251 engages an arcuate surface 261 on the arm 258 which terminates the movement of the clock mechanism and said arbor 234. When this occurs the arrangement of the contacts is such that the circuit through the spring leaf 246 is closed and that through the spring leaf 245 is opened. The device can be manually reset by rotating the finger piece 227 in a clockwise direction as viewed in Figs. 2 and 5. To limit such movement a stop 262 is employed which is attached to the arm 258 and which engages the surface of the disk 251.

The manner of connecting up the various protective devices of the invention at the subscriber's station will now be described in detail. The side 13 of the line 12 is directly connected to contact 111 of the pressure responsive switch 403. The other contact 109 of said switch is connected to a resistance 263 by means of a conductor 264. The resistance 263 is located in close proximity to said pressure switch or may be made a part thereof by housing the same in some portion of case 104 of said pressure switch so that it becomes impossible to tamper therewith. Resistance 263 is connected by means of a conductor 264 with the contact 118 of thermostat 115. The spiral 117 of this thermostat is connected by means of a conductor 265 with another resistance 266 which is disposed in close proximity to the thermostat the same as the resistance 263. The resistance 266 is connected by means of a conductor 267 to a similar resistance 268 used in conjunction with the call device 15. This resistance is connected by a conductor 269 to the frame of the said call device, said frame being in turn directly connected to the two disks 251 and 252. The switch leaf 245 of call device 15 is connected to ground by a conductor 271 while the switch leaf 246 is connected by means of a conductor 272 to one end of the foil 124. The other end of the foil is connected by a conductor 273 to a resistance 274. This resistance and the resistance 268 are associated with the call device 15 and the foil 124 in identically the same manner as the resistances 266 and 263 previously referred to. A conductor 275 runs between the resistance 274 and another resistance 276. This resistance is in turn connected by means of a conductor 277 to the frame of the call device 16. A conductor 278 extends between the switch leaf 246 of call device 16 and the switch leaf 158 of cam key 128 as shown in Fig. 7.

Switch leaf 245 of call device 16 is grounded through a conductor 270. The conductor 178 of cam key 128 is grounded through another conductor 279. Switch leaf 142 of this cam key as shown in Fig. 7 is connected by means of a conductor 281 to a resistance 282. This resistance is in turn connected by means of a conductor 283 to a similar resistance 284. Resistance 284 is connected by means of a conductor 285 with the frame of the call device 17. The side 14 of the main line 12 is directly connected to the switch leaf 246 of said call device, while the leaf 245 of said call device is grounded through conductor 260. It will thus be seen that the protective devices are all connected in series in the operating circuit 11 and function as a plurality of switches, each capable of opening said circuit upon actuation thereof and certain of said switches grounding the circuit upon actuation. The switch 403 opens the circuit when changes in pressure occur. Thermostat 115 opens the circuit when changes in temperature occur. Window foil 124 opens the circuit in case the window is tampered with or broken and the cam key 128 opens and grounds the circuit when the circuit is desired to be manually opened. The three call devices 15, 16 and 17 each functions to open and ground the circuit a successive predetermined number of times when the trip holding the clock mechanism thereof inactive is released. The circuit 11 is a normally closed circuit, being energized from the generator 22, which circuit includes the line 12. The circuit 11 may be traced as follows: Commencing at generator 22 current flows through conductor 24, resistance 26, conductor 101, rheostat 102, conductor 103, con-

ductor 98, both of the coils 51 and 57 of relays 47 and 48, conductors 97 and 96 and up to the jack 79. Current enters the switch leaf 88 of said jack and flows successively through switch leaves 91, 89 and 87, leaving the said jack by means of the side 13 of the main line 12 which is connected thereto. Current further flows through the main line and up to the pressure switch 403. From the pressure switch the current flows through the conductor 264, resistance 263, conductor 264, 10 thermostat 115, conductor 265, resistance 266 and conductor 267 up to the call device 15. At the call device the current continues through resistance 268, conductor 269 and to disk 251 of said call device. The current continues from the said disk through the switch leaf 246, conductor 272 and through the foil 124. Current leaves the foil through conductor 273, flows through resistance 274 and conductor 275 up to the call device 16. Current then flows through said call device the same as the call device 15 and from the said call device to the cam key 128 through conductor 278. Current continues from the cam key 128, flows through conductor 283 and the call device 17 and back to the side 14 of the line 12. From the line 12 the current flows through the test jack 78 through conductor 94, coil 65 of relay 49 and conductor 95 to ground, the generator 22 being grounded through conductor 23 completes the circuit. When any of the switches constituting the protective device of the invention are opened or if the line is broken at any locality both of the relays 48 and 49 are deenergized and the springs 63 and 73 move the connectors 59 and 68 of said relays into engagement with the corresponding contact. This closes the switches 64 and 72 and closes the circuit 10. This circuit may be traced as follows: Commencing at generator 22 current flows through said circuit from the conductor 24 through the resistance 25 and the conductor 29. Current further flows through the various switches 64 and 72 to the conductor 32. From this conductor the current divides and passes through the recording device 18, bell 33 and annunciator 34. These devices are all grounded and the generator 22 being also grounded completes the circuit. The separate circuit including conductors 46, 45 and 31 and the lamp 35 energize said lamp when the arm 42 of the annunciator 34 drops and contacts with the contact 44. The light 35 when once actuated continues to operate until manually disconnected which is accomplished by resetting the annunciator. When the circuit is opened or grounded by actuation of one of the call devices 15, 16 or 17, the recording device 18 records the signal given by said call device and indicates the particular substation from which the call is received. The recording device 18 may be of any desired construction. This particular device forming no feature of the invention has not been described though it can readily be comprehended that any suitable construction such as is now well known in the art and used for similar purposes may be employed.

In the event that the circuit 11 is grounded at any locality outside of the central station C the coil 65 of relay 49 is shunted out and deprived of electric energy. When this coil becomes deenergized in this manner switch 72 is closed and the circuit 10 closed and the signals operated as previously described.

To make it impossible to shunt out any of the protective switches or the protective device used in the operating circuit 11, the various resistances 263, 266, 268, 274 etc. which are disposed ad-

5 jacent the respective protective device are employed. The circuit 11 is so balanced through the rheostat that the potential relay 47 maintains the switch 56 open. The said relays and the said resistances are so designed that if one of these resistances is shunted out the potential across the coil 51 of relay 47 is sufficiently increased 10 to cause the actuation of said relay. This closes switch 56 and the signal circuit 10 is energized 15 which causes operation of the various signals in the said circuit as previously described. If the line 12 should become shorted at any location or if any portion of the circuit 11 becomes shorted, the same will operate to shunt out one or more of the resistances 263, 266 etc. This will have the 20 same effect as shunting out the single resistance and will cause operation of relay 47 which energizes the signal circuit and operates the signals therein.

20 My invention is adapted to function if any possible combination of ground, short or open occurs. When the circuit 11 is opened at any locality either through the switches or being broken both relays 48 and 49 are operated which energizes the circuit 10. If a short occurs relay 47 alone is operated. If a ground occurs both relays 47 and 48 are operated. The same is true if both an open and a ground occur. If a short and an open occur relay 47 alone is operated and if a 25 short and a ground occur both relays 47 and 49 are operated. It will thus be seen that no matter what method of tampering with the system is employed an indication will be given at the central station. Furthermore the particular 30 sub-station at which the signal is given will be indicated on the recording device when the circuit is opened or tampered with at such sub-station.

35 The window foil 125 operates the call device 16. Inasmuch as the call device cannot be installed directly on the window, it becomes necessary to run wires from the foil to the said call device. If an ordinary circuit were used for such purpose it would be possible to shunt out the 40 foil and open the window without actuating the signalling system. To prevent this the secondary circuit 19 is employed which directly operates the call device. This circuit is actuated by the circuit 21. These two circuits are similar in 45 operation to the circuits 10 and 11 and are provided with similar protective devices by means of which it becomes impossible to tamper with the foil or to short out the same and through which actuation of the signals is made equally as positive as when the switch 403 or the thermostat 115 50 is operated. This is accomplished in the following manner:

55 For energizing the circuits 19 and 21 a battery 283 is employed which is connected at one end 60 to ground by a conductor 284. This battery is connected by another conductor 285 to two resistances 286 and 287. These resistances serve the same function as the resistances 25 and 26 and operate to control the voltage in the circuits 65 19 and 21. To the resistance 286 is connected a subscriber's operating line 288 which furnishes current to the circuit 21. An auxiliary line 289 is connected to the resistance 287 and serves to furnish current to the circuit 19.

70 The circuit 21 is divided into three parallel branch circuits 21e, 21f and 21g, there being one such circuit for each of the call devices used with the system. In the particular instance the circuit 21e serves the call device 15, and is actuated 75 by the thermostat 116, circuit 21f serves the call

device 16 and is actuated by foil 125 while the circuit 21g serves the call device 17 and is actuated by cam key 129. Inasmuch as all of these circuits are identical in all respects and in the operation thereof, only the circuit 21f will be described in detail.

5 In the circuit 21f are provided three relays 291, 292 and 293 which are identical with the relays 47, 48 and 49. The relay 291 comprises a coil 294 and two contacts 295 and 296 adapted to be 10 connected together through a connector 297 operated by a plunger 298 movable within the coil 294. These contacts and connector form a switch indicated by the reference numeral 280. A spring 330 holds the switch 280 open. Relay 15 291 is a potential relay the same as the relay 47. Relay 292 comprises a coil 299, two contacts 301 and 302 and a connector 304 operated by a plunger 305 movable within the coil 299. This 20 connector and contacts constitute the switch indicated in its entirety by the reference numeral 290. A spring 300 serves to close the said switch when the relay is deenergized. Relay 293 similarly comprises a coil 306, two contacts 307 and 308 and a connector 309 adapted to be operated 25 by a plunger 311 movable within the coil 306. Said connector and contacts form a switch indicated in its entirety by the reference numeral 310. A spring 320 closes the switch 310 when relay 293 is deenergized.

30 The various relays 291, 292 and 293 are connected in the circuits 21 and 19 in the following manner: The circuit 21f includes a conductor 312 which is connected to the line 288 and to a rheostat 313. Rheostat 313 is connected by means 35 of a conductor 314 with the coils 294 and 299 of relays 291 and 292. These coils are further connected together by means of a conductor 315 which in turn is connected to a conductor 316. Conductor 316 is connected to one end of the foil 125. The other end of the foil is connected by 40 means of a conductor 317 to a resistance 318. Resistance 318 is connected by means of a conductor 319 to one end of the coil 306 of relay 293. The other end of said relay is connected by a 45 conductor 321 to ground. It will thus be found that the two coils of the relays 291 and 292 are connected in parallel and in series with the foil 125 and the coil of the relay 293, the said circuit receiving energy from battery 283 through the 50 resistance 286. The circuit 21f is a normally closed circuit and when closed maintains the three switches 280, 299 and 310 open. The rheostat 313 is adjusted so that if the resistance 318 is shorted out, the potential across the coil 294 55 increases sufficiently to actuate the relay 291 which closes the switch 280.

55 The line circuit 19 as previously stated includes the auxiliary line 289. This line is connected by 60 means of conductors 322, 323 and 324 to the contacts 295, 301 and 307 of switches 280, 290 and 310 respectively. The other contacts 296, 302 and 308 of said switch are connected by conductors 325, 326 and 327 to a common conductor 328 which in turn is connected to the electromagnet 65 192 of call device 16. The other side of this electromagnet is connected by a conductor 329 to ground. It will hence be seen that when any of the three switches 280, 290 and 310 are closed that a circuit is completed from the battery 283 70 through the electromagnet 192 of said call device to the ground. This circuit actuates the call device which in turn operates the signal circuit and at the same time causes the recording device 18 to function. In order to render the call de- 75

vice 15 absolutely positive the disk 252 and switch leaf 245 are employed. While the circuit is held open through the disk 251 and switch leaf 246 the same is being grounded through the other disk 5 and switch leaf. This causes an alternate operation of the circuit through the relays 49 and 47 which procures positive energization of the circuit 10.

The relays 291, 292 and 293 and the call device 16 may be conveniently placed within a single case and the said case locked so that access thereto is prevented. All of the wire of the circuit 19 may hence be concealed and only the wiring of circuit 21 exposed. Any tampering 15 with the circuit 21 will cause actuation of the circuit 19 the same as described in conjunction with the circuits 10 and 11. Actuation of circuit 19 procures the corresponding actuation of circuits 11 and 10 and the rendering of the 20 signal.

The circuits 21e and 21g are connected with the thermostat 116 and the cam key 129 respectively. Inasmuch as these circuits are identical with the circuit 21f and the manner of connecting the same is identical with that previously described, the said circuits will not be described in detail.

My invention operates in the following manner: If the pressure switch 403 is opened or if the thermostat 115 is opened circuit 11 is opened and relays 48 and 49 are deprived of energy and the switches 64 and 72 close energizing circuit 10. This operates the various signals 33, 34 and 35. The same is true if the foil 124 is broken. If the switch 128 is operated manually by swinging the handle 168 in either direction the circuit is first opened and then grounded. This causes the operation of first both relays 48 and 49 and then relays 47 and 49, making the actuation of the 40 various signals absolutely positive. If an attempt is made to shunt out any of the resistances 263, 266, 274, 282 or 284, potential relay 47 is caused to operate which again energizes circuit 18 and operates the signals. If an attempt is 45 made to ground the circuit at any locality in the subscriber's station S both relays 47 and 49 operate and the signal is given. If the line is both open and grounded then relay 49 alone operates. It will hence become apparent that it is practically impossible to tamper with the system without procuring an indication at the central station. If the window foil 125 be broken or if the 50 resistance 318 be shunted out or if the circuit 21f be shorted or grounded, the three relays 55 291, 292 and 293 act in identically the same manner as the relays 47, 48 and 49 and procure energization of the circuit 19. This has the effect of operating the call device 16. Call device 16 successively opens and grounds the circuit 11 60 thereby procuring actuation of the various signals in the central station. At the same time the call device operates the recording device 18 which advises the attendant of the particular location from which the call originates. The same is true 65 in the event the thermostat 116 is operated or the cam key 129, the said results being procured through the circuits 21e and 21g and circuit 19 in identically the same manner as described in conjunction with the window foil 125, and its 70 associated circuits.

My invention is highly advantageous in that a comparatively simple and practical system is provided by means of which any desired kind of protection may be rendered. By means of the 75 circuits employed it becomes practically impos-

sible to tamper with the system without causing a signal. The invention will operate indefinitely and any failure whatsoever in the system will be manifest by the operation of the signals. The system may be periodically tested to determine 5 leakage in the circuits. The number of units in the system may be increased or reduced at any time and by means of the variable resistances and rheostats employed the circuit is balanced for such change of conditions. The system is 10 easy to install and can be used with any type of building or similar structure. Any combination of the services desired may be readily procured. This system can be maintained at a 15 moderate expense.

Changes in the specific form of my invention, as herein disclosed, may be made within the scope of what is claimed without departing from the spirit of my invention.

Having described my invention, what I claim 20 as new and desire to protect by Letters Patent is:

1. In a protective signal system, a normally closed operating circuit, a source of electrical energy in said circuit, a normally energized potential relay having a winding in said circuit, said relay being adapted to be actuated upon the potential reaching a predetermined value, a protective device in said circuit, a resistance in said circuit in series with said protective device and positioned in close proximity thereto, an adjustable resistance in said circuit positioned at the locality of said relay, means for adjusting said resistance to prevent normal actuation of the relay when both of the resistances are in series in the circuit, and a signal operated by said 35 relay.

2. In a protective signal system for remote signalling, a normally closed operating circuit including a line running between a central station and a subscriber's station and having a loop disposed within said subscriber's station, a source of electrical energy at the central station grounded on one side and connected on the other side to one side of the line, the other side of the line being grounded in the central station, a relay at 40 said central station having a signalling switch and a coil, said coil being connected in said operating circuit, a signal circuit at said central station, said signalling switch of said relay being connected in said signal circuit, a signalling 45 device in said signal circuit, a recording device in said signal circuit, a call device at said subscriber's station having a coil and a code switch, said code switch being connected in the loop of said operating circuit and being adapted to operate 50 said recording device through said relay, a normally closed subscriber's operating circuit at said subscriber's station having a run connected at one end to a grounded source of electrical energy and at its other end to a ground, a relay at said 55 subscriber's station having a coil and a switch, said coil being connected in said subscriber's operating circuit near said ground, a secondary circuit at said subscriber's station, the switch of said second named relay being connected in said 60 secondary circuit, said coil of said call device being connected in said secondary circuit, and a protective switch in said subscriber's operating 65 circuit.

3. In a protective signal system for remote 70 signalling, a normally closed operating circuit including a line running between a central station and a subscriber's station and having a loop disposed within said subscriber's station, a source of electrical energy at the central station grounded 75

on one side and connected on the other side to one side of the line, the other side of the line being grounded in the central station, a relay at said central station having a signalling switch and a coil, said coil being connected in said operating circuit, a signal circuit at said central station, said signalling switch of said relay being connected in said signal circuit, a signalling device in said signal circuit, a recording device in said signal circuit, a call device at said subscriber's station having a coil and a code switch, said code switch being connected in the loop of said operating circuit and being adapted to operate said recording device through said relay, a normally closed subscriber's operating circuit at said subscriber's station having a run connected at one end to a grounded source of electrical energy and at its other end to a ground, a relay at said subscriber's station having a coil and a switch, said coil being connected in said subscriber's operating circuit near said ground, a secondary circuit at said subscriber's station, the switch of said second named relay being connected in said secondary circuit, said coil of said call device being connected in said secondary circuit, a potential relay at said subscriber's station having a coil and a switch, said potential relay coil being connected in said subscriber's operating circuit, and said potential relay switch being connected in said secondary circuit, a protective switch in said subscriber's operating circuit, and a resistance in said subscriber's operating circuit in series with said protective switch and in close proximity thereto.

4. In a protective signal system for remote signalling, a normally closed operating circuit including a line running between a central station and a subscriber's station and having a loop disposed within said subscriber's station, a source of electrical energy at the central station grounded on one side and connected on the other side to one side of the line, the other side of said line being grounded in the central station, a relay at said central station having a signalling switch and a coil, said coil being connected in said operating circuit, a potential relay at said central station having a signalling switch and a coil, the coil thereof being connected in said operating circuit, a protective device at said subscriber's station in said loop, a resistance in series with said protective device and in close proximity

thereto, a signal circuit in said central station, both of said switches being connected in said signal circuit and signalling means in said signal circuit operated by either of said relays.

5. In a protective signal system, a normally closed operating circuit including a main line connected at one side to a ground, a grounded source of electrical energy, connected to the other side of the line, a normally energized relay having a coil connected in said circuit in proximity to said ground, a switch mechanism in said circuit, said switch mechanism including a pair of normally closed switch elements, and a pair of normally open switch elements, one thereof being grounded, said mechanism being adapted upon actuation to first open said first named switch elements and to thereafter close said second named switch elements to first open and then ground said circuit, and a signal operated by said relay. 5

6. In a protective signal system, a normally closed operating circuit including a main line connected at one side to a ground, a grounded source of electrical energy connected to the other side of the line, a normally energized relay having a coil connected in said circuit in proximity to said ground, a call device, said call device having a switch mechanism in said circuit adapted to successively open and ground said circuit, actuating means for said switch mechanism, a trip including a coil for releasing said actuating means, a secondary circuit including the coil of said trip for operating said trip, a normally closed subscriber's operating circuit for energizing said secondary circuit, and a protective device in said last named circuit. 20

7. In a protective signal system, a normally closed operating circuit, said circuit having a run grounded at both ends, a protective device in said circuit, a relay in said circuit between one of 40 said grounds and said protective device, said protective device including two switches, one of said switches being normally closed and opening said circuit upon actuation, the other of said switches being normally open and having a switch element connected to said circuit, and a circuit connected to the other of said switch elements and to a ground in proximity to said protective device, and means for simultaneously operating said switches. 45

CLARENCE C. C. EGGRERS. 50
